US00D992932S

(12) **United States Design Patent** (10) **Patent No.:** **US D992,932 S**
(45) **Date of Patent:** **** Jul. 25, 2023**

(54) **MATTRESS**

(71) Applicant: **Casper Sleep Inc.**, New York, NY (US)

(72) Inventors: **Martin Kay**, San Francisco, CA (US); **Ara Acle**, Oakland, CA (US); **Rebecca Cockerham**, Brooklyn, NY (US); **John-Rhys Newman**, Los Angeles, CA (US)

(73) Assignee: **Casper Sleep Inc.**, New York, NY (US)

(**) Term: **15 Years**

(21) Appl. No.: **29/756,427**

(22) Filed: **Oct. 28, 2020**

Related U.S. Application Data

(62) Division of application No. 29/703,367, filed on Aug. 27, 2019, now Pat. No. Des. 908,398.

(57) **CLAIM**

We claim the ornamental design for a mattress, as shown and described.

DESCRIPTION

FIG. 1 is a front perspective view of a mattress in accordance with the present design;

FIG. 2 is a top view thereof;

FIG. 3 is a bottom view thereof;

FIG. 4 is a left view thereof;

FIG. 5 is a right view thereof;

FIG. 6 is a front view thereof; and

FIG. 7 is a rear view thereof.

FIG. 8 is a front perspective view of a second embodiment of a mattress in accordance with the present design;

FIG. 9 is a top view thereof;

FIG. 10 is a bottom view thereof;

FIG. 11 is a left view thereof;

FIG. 12 is a right view thereof;

FIG. 13 is a front view thereof; and,

FIG. 14 is a rear view thereof.

The dashed lines in the figures form a part of the claimed design.

1 Claim, 14 Drawing Sheets
